US00D612019S

(12) **United States Design Patent**
Williams et al.

(10) **Patent No.:** US D612,019 S
(45) **Date of Patent:** ** Mar. 16, 2010

(54) **COUPLING BODY**

(75) Inventors: **Randall Scott Williams**, Minneapolis, MN (US); **Patrick Thomas Gerst**, Oakdale, MN (US); **Grant Armin Wilhelm**, Plymouth, MN (US); **James Mark Hanson**, Woodbury, MN (US)

(73) Assignee: **Colder Products Company**, St. Paul, MN (US)

(**) Term: **14 Years**

(21) Appl. No.: **29/331,581**

(22) Filed: **Jan. 28, 2009**

(51) **LOC (9) Cl.** 23-01

(52) **U.S. Cl.** D23/262

(58) **Field of Classification Search** D23/259-269; 285/11-12, 7, 177, 394-395, 307, 358, 179-183, 285/423, 356, 303, 337, 1, 53, 404, 112, 285/367, 373, 915; 4/321, 323; 292/58-59; D24/127-129

CLAIM

The ornamental design for the coupling body, as shown and described.

DESCRIPTION

FIG. 1 is a first top perspective view of the coupling body.

FIG. 2 is a second top perspective view thereof.

FIG. 3 is a top view thereof.

FIG. 4 is a bottom view thereof.

FIG. 5 is a side view thereof.

FIG. 6 is an end view thereof; and,

FIG. 7 is an opposite end view thereof.

The other side is identical to the side shown in FIG. 5. The broken line showing aspects of the coupling body is for the purpose of illustrating environmental structure and forms no part of the claimed design.
